Manufacturing Corporation, Long Island City, N. Y.,
a corporation of New York

Application January 4, 1954, Serial No. 402,096

19 Claims. (Cl. 153—1)

The present invention relates to a machine and method for simultaneously and continuously securing two elongated metal strips to opposite side edges of an elongated strip of fabric.

An object of the invention is to simultaneously and continuously fold the edge portion of two strips of metal about opposite edges of the same strip of fabric.

A further object of the invention is to enable the production of a coil of material, the material comprising two elongated strips of metal, an edge portion of each of which are folded into secure engagement with the opposite side edges of a single elongated strip of fabric.

It is also an object of the invention to enable the continuous bending of an edge portion of each of two continuous strips of metal while maintaining the strips in predetermined relationship, and moreover, to accomplish this at the same linear rate upon both strips while avoiding any tendency of the metal to buckle or bow.

Another object of the invention is to enable a strip of fabric to be continuously and positively fed into securing relationship with the folded portion of each of the metal strips in unwrinkled condition and without any appreciable tendency to become disengaged from the aforesaid folded portions during prolonged operation of the machine.

Other and further objects of the invention will become apparent from the following description of the invention taken in conjunction with the accompanying drawings in which:

Figure 1 is a side elevational view of the machine;

Figure 2 is a fragmentary plan view with the fabric guide in section;

Figure 3 is a sectional view taken on the line 3—3 of Figure 2;

Figure 4 is a fragmentary perspective view showing the fabric guide, the placing of the fabric upon the partly formed strip of metal and the first operation which leads to the securing of the metal strip to the fabric;

Figure 5 is a diagrammatic view showing the gear train employed to drive the metal forming rolls;

Figure 6 is a fragmentary view showing the metal guide and the first set of forming rolls as well as the two strips of metal in operative relationship as they are being formed;

Figure 6a is a perspective representation of the shape which the edge portions of the metal strips have been forced to assume when they emerge from the forming rolls shown in Figure 6;

Figures 7 and 7a and 8 and 8a are similar to Figures 6 and 6a, respectively, and show the metal strips as they are acted upon by each successive pair of forming rolls;

Figures 9 and 9a and 10 and 10a are also similar to Figures 6 and 6a, respectively, with the exceptions that the metal guide has terminated and is no longer present and a strip of fabric has been placed upon the strips of metal;

Figure 11 is a perspective view of one form of a suit-

2

able metal guide used to retain the metal strips in operative relationship to the forming rolls;

Figure 12 is a fragmentary perspective view of the product as it emerges from the machine;

5 Figure 13 is a fragmentary perspective view of the product with the metal sheets unfolded preparatory for use;

10 Figure 14 is a fragmentary perspective view of the product in use forming a flexible connection between a furnace and the ductwork used to convey the heated air away from the furnace; and

15 Figure 15 is a fragmentary perspective view showing an alternative form of pulling arms which possess a reduced tendency to cause buckling of the metal strips.

15 Referring to Figure 1 of the drawing, two strips of metal 10, 10' are continuously withdrawn from a supply coil (not shown) and pulled into and through two juxtaposed laterally spaced parallel series of forming rolls indicated generally at 20. The forming rolls are driven by

20 means of motor 11, belt 18 and pulley 19. A strip of fabric 30 is fed from a supply (not shown) and slid along an overhead chute 31 to a fabric guide 32 supported by uprights 34. A weight 33, secured to the chute 31, as shown, is placed upon the fabric 30 and serves, together

25 with the friction of the fabric against the chute itself, to provide suitable tension to the fabric supplied. The fabric 30 passes under idler roll 35 which presses the fabric 30 against the surface of the fabric guide 32, thus additionally reducing the danger of having the fabric wrinkle.

30 The two strips of metal 10, 10', together with the superimposed fabric 30 emerge from the forming rolls 20 and are permanently secured together by pressure crimping rolls indicated generally at 40. The resulting product advances beneath roller 50, contact of the product serving

35 to rotate roller 50 to actuate a counting device 51 to indicate the length of product produced by operation of the machine.

The product as continuously produced is fastened to a coiling reel indicated generally at 70 by leading the se-

40 cured superimposed strips of metal and fabric over one of the bars 71 and under the next succeeding bar to thereby hold the advancing product by virtue of the natural resiliency of the metal strips.

45 The coiling reel 70 is driven by motor 72, power from the motor being transferred to the coiling reel by means of a reduction gear 73, belt 74, variable speed reducing device 75 and belt 76. The belt 76 is connected to a section of the variable speed reducing device 75 having a diameter of proper size to cause the bars 71 on the coiling reel 70 to advance at the same, or slightly greater, linear velocity than the product which emerges from the machine. If a slightly greater velocity is employed, slippage of belts 74 and 76 would occur and provide a constant torque to coiling reel 70 which reduces the tendency of the metal strip 10 and 10' to slip.

50 After the desired length of product has been produced and coiled on coiling reel 70, the product is severed by cutting device 80, and slid off the bars 71 on the coiling reel 70 and packaged as a coil.

60 In operation, the motor 11 drives the forming rolls 20 at a rate sufficient to produce 20 feet of product per minute. Accordingly, motor 72 is operated at 1,750 R. P. M., a reduction gear ratio of 80 to 1 is employed

65 and the variable speed reducing device is set to produce a 3 to 1 reduction in belt velocity to thereby provide bars 71, which move in a circle of 30 inch diameter, with a velocity which coincides with the rate of travel of the material produced.

70 Motors 11 and 72 are preferably supplied with electric current from a common circuit so that both may be actuated and stopped simultaneously with a common switch. If desired, the counting device 51 may be con-

nected with an electrical relay which breaks the electric circuit to the motors 11 and 72 so that the machine may be automatically stopped when the desired length of product has been produced.

As is evident from Figure 1, the juxtaposed laterally spaced parallel series of forming rolls 20, pressure crimping rolls 40, counting device 51 and cutting device 80 are all mounted upon table 81. The table 81, as can be seen in Figures 1 and 2, has apertures 82 and 83 to receive the forming rolls 20 and the pressure crimping rolls 40, respectively.

With further reference to Figure 2, two laterally spaced parallel series of forming rolls are employed. As can be seen from Figure 3, each of the series of forming rolls contains successive mating pairs of vertically aligned rolls, the forming rolls and their action being more clearly shown in Figures 6-10 of the drawing.

The metal strips 10 and 10' are pulled into the forming rolls 20 through a metal guide 12 shown in perspective in Figure 11. As can be seen, the metal guide is formed in two sections. In the first section 13, both lateral edges of each of the metal strips are engaged, the outer edges being engaged by the surfaces 14 and the inner edges being engaged by the surfaces 15. The first section of the metal guide terminates immediately before the first set of spaced forming rolls 21, 21', the termination point 16 being shown in Figure 2. In the second section 17 of the metal guide 12, only the inner edges of the metal strips are engaged, to thereby permit the forming rolls to form the outer edge portions of the metal strips 10, 10' without interference.

Rollers 21, 21' form the outer edge portions of the aligned metal strips 10, 10' into the configuration shown in Figure 6a. The partially formed metal strips which emerge from the forming rolls 21, 21' are then engaged by forming rolls 22, 22' which further form the metal strips into the configuration shown in Figure 7a. The metal strips which emerge from the rolls 22, 22' are then still further formed by forming rolls 23, 23' which function to bend the outer extremity of the metal strips into an upright position as shown in Figures 8 and 8a.

As can be seen from Figures 2, 3 and 4, the fabric guide 32 extends from above to a position between the forming rolls 23 and 24. The fabric 30 slides over the convex surfaces of the guide 32 and is thereby introduced into the nip between the forming rolls 24, 24'. The fabric guide 32 terminates in a presser tongue 36 positioned between the laterally spaced forming rolls and extends beyond the forming rolls 24. This tongue 36 serves to hold the fabric in place and additionally functions together with the curvature of the fabric guide 32 to properly position the fabric 30 in unwrinkled condition upon the metal strips 10, 10'. The fabric guide 32 is curved, both along its length and along its width. The curvature of the fabric guide 32 serves to prevent wrinkling of the fabric 30. Additionally, the fabric 30 is preferably provided with a sewn beaded edge portion at each of its longitudinal edges. The beaded edge portions of the fabric 30 do not stretch as readily as does the remainder of the fabric 30 and, accordingly, the fact that the fabric guide 32 is curved along its width, as shown in Figure 2, prevents the fabric 30 from being displaced to either side on the fabric guide 32. Preferably, the fabric guide 32 is tapered along its entire length from an enlarged entrance end to an exit end of the same width as the space between the upstanding edges of the metal strips 10, 10' to compensate for variations in the width of the fabric 30.

The metal strips 10, 10' together with the superimposed fabric 30 are then engaged by forming rolls 24, 24'. As can be seen from Figures 4 and 9, forming rolls 24, 24' possess a circumferential bead 26. This bead 26 serves to engage the fabric 30 and maintain the proper positioning of the fabric. The bead 26 is more effective when the fabric 30 is provided with a beaded edge portion, since in such event, it is more difficult for the edge of the

fabric 30 to ride out of its proper place. Forming rolls 24, 24' function to engage the outer extremities of the metal strips 10, 10' and fold these outer extremities over upon the edge portion of the fabric 30, as shown in Figures 4, 9 and 9a. Forming rolls 25, 25' continue this action as is clearly shown in Figures 10 and 10a.

The product emerging from forming rolls 25, 25' advances between pressure crimping rolls 41, 41', which serve to permanently secure the metal strips 10, 10' to the edge portions of the fabric 30 to continuously produce the product shown in Figure 12. It is not necessary to positively drive the crimping rolls 41, 41'. Instead, the crimping rolls are rotated by passage of the product therebetween, sufficient pressure being employed to securely attach the fabric 30 and the metal strips 10, 10'.

As is clearly shown in Figure 2, each of the laterally spaced vertically aligned pairs of forming rolls are mounted upon a common shaft so that metal strips 10, 10' are advanced at the same rate of speed. It should be obvious that the laterally spaced forming rolls may be separately mounted if desired, in which case, means must be provided to regulate the speed of at least one of the series of bending rolls in response to the movement of the metal strip engaged by the other series of bending rolls, as can be done in any suitable manner.

The forming action of each series of forming rolls upon only one edge of each of the metal strips serves to stretch the outer edge of the metal strips without stretching to a corresponding extent the remaining portion of the metal strips. As a result of this localized stretching action, the metal strips 10, 10' tend to bow. The direction of this bow is naturally in a direction away from the forming rolls which are the cause of the bow. In other words, the metal strips 10 and 10' which enter the forming rolls 20 in parallel alignment tend to cross one another in the coiled product. This undesirable bowing may be reduced to an insignificant degree by lengthening section 17 of the metal guide 12 and in this regard, section 17 may extend as far as cutting device 80. Another way of reducing the bowing to an insignificant degree is shown in Figure 2 of the drawing where arms 90 and 91 are secured to the table 81. The arms 90 and 91 extend beneath the metal strips 10 and 10' and engage and pull the inner edges of each of the metal strips 10 and 10'. Since the metal strips 10 and 10' are held securely by the pressure crimping rolls 40, 40', the pressure crimping rolls act as the point of a lever and the pull exerted by the arms 90 and 91 serve to stretch the entire metal strip to compensate for the localized stretching caused by the forming rolls to thereby counteract the natural bowing of the metal strips and reduce it to an insignificant degree.

Because of the narrow width of arms 90 and 91, a tendency for these arms to cause the metal strips to buckle instead of stretch has been observed. In such event, resort may be had to the alternative form of bow removal means illustrated in Figure 15. As can be seen, two elongated guides 130 and 131 are employed to slidably engage the inner edges of the metal strips 10 and 10'. The guides 130 and 131 are pivotally secured at their leading end, guide 131 being shown pivotally attached to table 81 between apertures 82 and 83 by rivet 132 and guide 130 being shown pivotally attached to table 81 by rivet 133. Rivet 133 may be attached to the guide 131, or a single rivet may be employed for both guides by suitably shaping the guides themselves. The trailing edge of each of the guides 130 and 131 are secured to table 81 near the cutting device 80 by means of bolts and nuts as shown. The table or the guides are slotted to enable suitable adjustment to thereby regulate the pull on the metal strips to a value sufficient to just remove the bow, the increased area of the metal strips which are placed under compression, e. g., the outer portion, eliminates the tendency of the metal strips

to buckle. The guides 130, 131 are shown in position in phantom lines in Figure 2.

The forming rolls are mounted upon common shafts which are journalled in side plate 92 and extend through side plate 93. Each of the side plates 92 and 93 are supported by table 81 and are each divided into an upper and lower side plate, respectively, which support the upper rollers 21-25 and the lower rollers 21' to 25', respectively. The upper and lower sections of the side plates 92 and 93 are fixed in position by bolts 94 and 95 and locking nuts 96 and 97, as can best be seen in Figure 3. The material passing between the forming rolls serves to maintain the upper and lower sections of the side plates 92 and 93 in spaced relation and the locking nuts 96 and 97 serve to define the maximum permissible spacing and, accordingly, the pressure imposed upon the material by the forming rolls. Since forming rolls 24, 24' and 25, 25' have to contend with the additional thickness imparted by the fabric 30, the upper and lower side plates must be maintained more closely together by the locking nuts 96 to prevent an undue proportion of strain being placed on forming rolls 24, 24'. When locking nut 96 is tightened, the strain is transferred preferentially to forming rolls 21, 21'. The foregoing difficulty may be circumvented by mounting each successive mating pair of vertically aligned rolls on separate side plates for separate adjustment.

Despite all of the foregoing precautions, variations in the thickness and surface friction of the stock material may occur, and in such event, slippage of one of the metal strips 10, 10' may be encountered. Such slippage not only causes creep, e. g., advance of, for example, the strip 10 at a greater speed than the strip 10', but in addition, sudden and unusual stresses are imposed upon one or more of the forming rolls which may cause a failure to occur in one or more of the forming rolls or their connecting shafts. This difficulty is usually only encountered during operation upon heavier gauge metal strips and may be mitigated by utilizing positively driven pressure rolls 42, 42' mounted upon common shafts 43, 43' of increased diameter with respect to the shafts upon which the remaining forming rolls are mounted. Pressure rolls 42, 42' are preferably mounted upon side plates separate from side plates 92 and 93 and the pressure upon these rolls is adjusted by means of locking nuts 44 on bolts 45 so that the pressure imparted by pressure rolls 42, 42' is sufficiently great to prevent the possibility of creep and is moreover adjusted to be greater than the pressure imparted by any of the forming rolls 21 to 25 and 21' to 25' to enable the pressure rolls 42, 42' and their common shafts 43, 43' to preferentially absorb any unusual strains which might occur and render unnecessary the over design as to strength and size of the forming rolls 21 to 25 and 21' to 25' and their connecting shafts. When operation upon light gauge metal only is contemplated, positively driven pressure rolls 42, 42' may be omitted and hence these rolls and their accompanying parts are shown in the drawing in phantom.

The forming rolls 21 to 25 and 21' to 25' are driven by motor 11, belt 18 and pulley 19, which is mounted upon shaft 101, which extends through plate 100 mounted on table 81. Plate 100 additionally carries shafts 102, 103 and 104, which can be seen in Figure 2. Further, shafts 101', 102', 103' and 104' are carried on plate 100 immediately below shafts 101, 102, 103 and 104 respectively. Shafts 101, 101', 102, 102', 103, 103', 104 and 104' carry power transmitting gears 105, 105', 106, 106', 107, 107', 108 and 108', respectively.

As can be seen from Figures 2 and 5, rotation of pulley 19 causes rotation of gear 105, which directly drives 124 and 125 which power forming rolls 24 and 25. Gear 124 additionally rotates gear 106 which in turn causes rotation of gears 123, 107, 122, 108 and 121, thus powering forming rolls 23, 22, and 21. Gear 125 meshes with

gear 125' to power forming roll 25'. Gear 125' in turn causes rotation of gears 105', 124', 106', 123', 107', 122', 108' and 121', thus powering forming rolls 24', 23', 22' and 21'.

- 5 When pressure rolls 42, 42' are employed, these rolls are positively driven by having gears 125 and 125' drive gears 46 and 46', respectively, which in turn drive gears 47 and 47', respectively. These last named gears power pressure rolls 42 and 42', respectively. The gears 46 and 46' are mounted upon shafts 48 and 48', respectively which are journalled in plate 100 and side plate 93.
- 10

The product as produced by the machine of the present invention is clearly shown in Figure 12. In use, a suitable length of the product is severed from a coil of the same 15 and opened into the form shown in Figure 13. The metal strips are then bent into the shape of the ducts to which they are to be attached and secured thereto in any suitable manner.

A typical utilization of the product is illustrated in 20 Figure 14 where it forms a flexible connection between a furnace F and the ductwork D which leads the heated air produced by the furnace to wherever the heated air is desired. The flexible connection prevents transmission of vibration from the blower in the furnace to the duct-work and, accordingly, acts to substantially reduce noise. Further, use of the flexible connection eases the problem of exactly fitting the ductwork to the furnace, since any 25 error is compensated for by the flexibility of the fabric 30.

The term "fabric" as employed herein is intended to 30 include any flexible, yieldable sheet material, as for example, canvas, woven asbestos webbing or listing tape, sheets of rubber and synthetic resinous materials such as "neoprene" vinyl polymers and copolymers and woven and unwoven fabrics coated with rubber or synthetic resinous materials. Some of these flexible yieldable sheet 35 materials cannot be satisfactorily sewn, in which case, a thickened margin may be employed in place of a sewn marginal bead.

I claim:

- 40 1. An apparatus for simultaneously and continuously attaching a single marginal portion of two elongated metal strips to opposite side edges of an elongated strip of fabric which comprises two juxtaposed laterally spaced apart parallelly aligned series of bending rolls, guide means 45 having substantially U-shaped portions surrounding and engaging the interior edges of the two elongated metal strips to guide the metal strips longitudinally in a predetermined widthwise relationship with respect to said series of bending rolls and into gripping engagement therewith, each of said series of bending rolls engaging the outer marginal portion of one of said metal strips and being capable of first bending said marginal portion of said metal strip to form a side of a trough and then bending said marginal portion over upon the remainder of 50 said strip to clampingly engage a fabric resting upon said remainder of said strip, guide means for introducing said elongated strip of fabric upon said metal strips whereby said metal strips with the fabric thereon will be advanced together between the rolls of said series of bending rolls which bend said marginal portions of said metal strips into clamping engagement with said fabric strip at each of its side edges.

2. An apparatus as recited in claim 1 in which said 55 guide means for introducing said elongated strip of fabric upon said metal strips is positioned between longitudinally spaced adjacent rolls of said series of bending rolls whereby said elongated strip of fabric is placed upon said metal strips after said metal strips have been bent into the shape of a trough.

3. An apparatus as recited in claim 1 in which said 60 means engaging the two elongated metal strips to guide the same longitudinally into gripping engagement with the said series of bending rolls comprises two sections, a first section in which both the inner and outer side edges 65 of said metal strips are engaged and a second section in

which only the inner edges of said metal strips are engaged, said first section terminating before the position where each of said series of bending rolls engages said metal strips.

4. An apparatus as recited in claim 3 in which said second section of said metal guide means terminates at a position before the point where said fabric is placed upon said metal strips.

5. An apparatus as recited in claim 2 in which said fabric guide is curved both along its length and along its width to prevent wrinkling of said fabric upon deposition upon said metal strips.

6. An apparatus as recited in claim 1 in which idler pressure crimping rolls are employed to permanently secure the outer extremities of said metal strips to the edge portions of said fabric.

7. An apparatus as recited in claim 1 in which a coiling reel driven at least at the same peripheral velocity as the velocity at which the metal strips are advanced is employed to form a coil of the secured metal strips and fabric.

8. An apparatus as recited in claim 7 in which a constant torque is applied to said coiling reel.

9. An apparatus as recited in claim 1 in which a pair of fixed arms are placed in sliding contact with the interior edges of each of said metal strips at a location where the outer marginal portions of said metal strips have been bent into clamping engagement with said fabric strip to pull said metal strips outwardly and thereby remove the natural bow produced in said metal strips by said series of bending rolls.

10. An apparatus as recited in claim 1 in which each of said series of bending rolls contains successive positively driven, vertically aligned, mating bending rolls and independently mounted pressure rolls are employed to press said edge portions of said metal strips upon said strip of fabric, said pressure rolls being carried by a common shaft of greater diameter than any of the shafts which carry said bending rolls.

11. A method of continuously producing a stock material in which each marginal side edge of an elongated strip of fabric is securely attached to a separate elongated strip of metal which comprises continuously longitudinally advancing two elongated metal strips in predetermined widthwise relationship with the interior edge portions of said metal strips being confined by guide means, simultaneously forming the outer edge portions of each of said metal strips while maintaining the inner edges of said metal strips in predetermined position so that the said metal strips together form a trough, continuously placing a strip of fabric upon said trough, continuously bending the outer edge portions of each of said metal strips over upon said strip of fabric and continuously applying pressure to the folded over portion of said metal strips to securely attach the edge portions of each of said metal strips to each of the side edges of said strip of fabric.

12. A method of continuously producing a stock material in which each marginal side edge of an elongated strip of fabric is securely attached to a separate elongated strip of metal which comprises progressively longitudinally advancing two elongated metal strips in predetermined widthwise relationship, progressively applying pressure to form the outer marginal portions of each of said metal strips while maintaining the inner edges of said metal strips in predetermined position so that the said metal strips together form a trough, progressively placing a strip of fabric upon said trough, progressively applying pressure to bend the outer marginal portions of each of said metal strips over upon said strip of fabric and progressively applying pressure to the folded over portion of said metal strips to securely attach a marginal portion of each of said metal strips to each of the side edges of said strip of fabric.

13. The method as recited in claim 12 in which said

metal strips are securely attached to the edge portions of each of the side edges of said strip of fabric by crimping the folded over portions of said metal strips at spaced points.

14. A method of producing a stock material in which each marginal side edge of an elongated strip of fabric is securely attached to a separate elongated strip of metal comprising progressively longitudinally advancing two elongated metal strips along parallel paths in predetermined widthwise relationship, progressively placing a strip of fabric upon said metal strips, progressively applying pressure to the outer marginal portions of each of said metal strips to bend the outer marginal portions of each of said metal strips over upon the strip of fabric, progressively applying pressure to the bent over portion of said metal strips to securely attach a marginal portion of each of said metal strips to each of the side edges of said strip of fabric and coiling the secured together stock material while said pressure is being progressively applied along the length of said metal strips.

15. A method as recited in claim 14 in which said coiling is performed with the application of a constant torque to the coil.

16. A method as recited in claim 14 in which the interior edges of said metal strips is maintained in predetermined position while said progressive pressure is applied by means of forces applied both forwardly and rearwardly along the length of said metal strips with respect to the region of application of said progressive pressure.

17. A method of producing a coil of a stock material comprising two elongated metal strips secured to opposite side edges of a fabric strip in which said metal strips overlap each other in said coil comprising progressively bending a marginal portion of each of said metal strips to secure said marginal portion of each of said metal strips to opposite side edges of said fabric strip and simultaneously coiling said secured together strips.

18. A method of producing a coil of a stock material comprising two elongated metal strips secured to opposite side edges of a fabric strip in which said metal strips overlap each other in said coil comprising continuously and progressively bending the outer marginal portion of each of said metal strips to secure said outer marginal portions of said metal strips to the opposite side edges of said fabric strip to continuously produce a stock material in which said metal strips overlap each other and simultaneously coiling said stock material with said metal strips in overlapped position.

19. A method comprising continuously advancing two elongated metal strips and a single elongated fabric strip in parallel paths with said metal strips at least partially superimposed and said fabric strip under tension, continuously bending the outer marginal portion of each of said metal strips to secure the outer marginal portions of said metal strips to opposite side edges of said fabric strip to produce an secured together stock material in which said metal strips overlap each other and continuously coiling said secured together stock material under constant torque as said metal strips are secured to said fabric strip.
